UNITED STATES PATENT OFFICE.

HERMANN LINDEMANN, OF REICHENBACH, GERMANY.

GRINDER.

SPECIFICATION forming part of Letters Patent No. 602,860, dated April 26, 1898.

Application filed May 21, 1897. Serial No. 637,538. (No model.)

To all whom it may concern:

Be it known that I, HERMANN LINDEMANN, a subject of the German Emperor, residing at Reichenbach, Kingdom of Saxony, Germany, 5 have invented certain new and useful Improvements in Grinders, of which the following is a specification, reference being had therein to the accompanying drawings.

This invention relates to certain new and 10 useful improvements in grinders, and relates more particularly to that class employed for grinding stone, iron, and steel or other like materials to obtain a perfectly smooth surface on the same; and the invention has for 15 its object to obtain a larger grinding-surface on the face of the grinder and by this means increase the efficiency of the same.

The invention has for its further object to 20 construct a grinder having a grinding-surface formed of a series of removable blocks of stone, emery, or other suitable material, which are locked in close contact with one another in a radial disk in a manner to bring the polishing or grinding face of the blocks perfectly 25 flush with each other, and thereby form a solid grinding or polishing surface.

A further object of the invention is to construct a grinder to which an auxiliary radial disk may be attached and the grinding or 30 polishing surface of the grinder thereby increased; and with the above and other objects in view the invention finally consists in the novel construction, combination, and arrangement of parts to be hereinafter more specifically described, and particularly pointed out 35 in the claim.

In describing the invention in detail reference is had to the accompanying drawings, forming a part of this specification, and 40 wherein like letters of reference indicate similar parts throughout the several views, in which—

Figure 1 is a plan view, partly broken away and with the auxiliary radial disk shown in 45 dotted lines. Fig. 2 is a vertical sectional view of the grinder with auxiliary radial disk in dotted lines. Fig. 3 is a cross-sectional view of a portion of the grinder and blocks. Fig. 4 is a perspective view of one of the 50 grinding-blocks. Fig. 5 is a perspective view of one of the securing-keys. Fig. 6 is a side view of the same. Fig. 7 is a top plan view

of the same. Fig. 8 is a plan view of one of the sections forming the radial auxiliary disk. Fig. 9 is a view taken on the line X X of Fig. 55 8 as seen from the direction indicated by the arrow.

Referring now to the drawings by reference-letters, *a* indicates the radial disk, formed with a central hub *b*, a circumferential flange 60 or rim *c* extending around the outer periphery of the disk. A raised radial flange *d* extends around the one disk and is connected to the hub *b* and the circumferential flange *c* by ribs *e e*. The disk *a* is provided around 65 its periphery, inside the flange *c*, with raised portions or bushings *f f*, which, together with the radial flange *d*, are provided with apertures *g g* to receive the shank *h* of the securing-wedge *k*. These securing-wedges *k* are 70 provided with inclined sides conforming to the inclined sides of the grinding or polishing blocks *e'*, which are preferably composed of emery, but may be made of any suitable material. The shanks *h h* are provided on 75 their upper ends with screw-threaded stems *h' h'* to receive the nuts *h² h²* for fastening the securing-wedge in position. To the central hub *b* is connected the driving-shaft *b'*, which may be screwed into the hub or other- 80 wise secured, as desired.

In Fig. 8 I have shown one section of the auxiliary radial rim or disk *a'*, these sections being provided on their ends and on their inner periphery with a flange *a²*, having ap- 85 ertures *a³ a³* to receive fastening-bolts for securing the sections together and to the flange *c* of the disk *a*, said sections being also provided with raised portions *f'*, having apertures *f²* to receive the shanks *h* of the securing-wedges. 90

The grinding or polishing blocks are ar- ranged in the grinder in a circle and are firmly held in engagement with each other by means of the wedges *k k*, the inclined faces of which 95 engage the inclined faces of the grinding-blocks, said wedges being drawn tight by means of the nuts on the screw-threaded stems of the shanks.

In case it is desired to increase the grind- 100 ing-surface of the grinder the auxiliary disk may be attached to the main disk in the manner heretofore described and the grinding-blocks secured in said auxiliary disk in the

same manner as described for the main disk, and it will be observed that any one of these blocks may be removed, as desired, and also that several sets of these grinding-blocks may be kept on hand, each set composed of different material, as may be required or desired for the different material upon which the grinder is being employed.

I claim—

10. A grinder consisting of a radial disk formed with a central hub, a circumferential flange or rim extending around the outer periphery of the disk, a raised radial flange extending around the one disk, and is connected to the

hub, a series of grinding-blocks secured in 15 said disk, said blocks being held in position by wedges engaging the disk, an auxiliary disk formed in sections and adapted to be secured to the main disk to receive grinding-blocks, to increase the grinding-surface of the 20 grinder, substantially as shown and described.

In testimony whereof I affix my signature in presence of two witnesses.

HERMANN LINDEMANN.
